(57) **CLAIM**

The ornamental design for a vehicle roof fairing, as shown and described.

DESCRIPTION

FIG. 1 is a front perspective view of a vehicle roof fairing showing my new design;

FIG. 2 is a front elevational view of the vehicle roof fairing of FIG. 1;

FIG. 3 is a rear elevational view of the vehicle roof fairing of FIG. 1;

FIG. 4 is a top plan view of the vehicle roof fairing of FIG. 1;

FIG. 5 is a bottom plan view of the vehicle roof fairing of FIG. 1;

FIG. 6 is a right side elevational view of the vehicle roof fairing of FIG. 1; and,

FIG. 7 is a left side elevational view of the vehicle roof fairing of FIG. 1.

In the drawings, the broken lines show a vehicle and form no part of the claimed design.

1 Claim, 4 Drawing Sheets
